UNITED STATES PATENT OFFICE.

WALTER R. EKINS, OF ST. LOUIS, MISSOURI, ASSIGNOR TO BROWN SHOE COMPANY, INC., OF ST. LOUIS, MISSOURI, A CORPORATION OF NEW YORK.

SHOE AND METHOD OF MAKING THE SAME.

Application filed June 26, 1925. Serial No. 39,663.

To all whom it may concern:

Be it known that I, WALTER R. EKINS, a citizen of the United States of America, a resident of the city of St. Louis and State of Missouri, have invented certain new and useful Improvements in Shoes and Methods of Making the Same, of which the following is a full, clear, and exact description, reference being had to the accompanying drawings, forming a part of this specification.

This invention relates generally to improvements in shoes and methods of making the same, and more specifically to an attachment for a shoe whereby the heel portion of said shoe is prevented from accidentally moving relative to the heel of the wearer when said wearer of said shoe is walking.

Prior to this invention it has been found necessary, particularly in the case of women's shoes of the low type, to provide some means for preventing the heel portion of the shoe from accidentally moving relative to the heel of the wearer when the shoe is flexed in walking. This relative movement between the heel portion of the shoe and the heel of the wearer is objectionable for the reason that it has a tendency to wear the stockings at the points where the rubbing action takes place, and also because it often causes formation of sores or blisters on the wearer's heels. The relative movement of the heel portions of shoes of the type mentioned and the heels of the wearers of said shoes was caused to a large extent by the fact that the inner faces of the inner quarters of said shoes were rather smooth, and to eliminate this movement manufacturers of shoes have been arranging pieces of material having comparatively rough faces within the shoes at the heel portions thereof. The pieces of material mentioned were, of course, of some thickness and said pieces of material were secured on the inside faces of the shoes so that they extended into said shoes a distance equal to the thickness of said pieces. As a consequence of the presence of these pieces of material shoulders were formed within the shoes which tended to render the use of said shoes uncomfortable, and also as there is sure to be some slight movement of the heel portion of a shoe relative to the heel of the wearer, the likelihood of the stockings being worn or sores or blisters formed on the heels of the wearer was increased over what

it was before the practice of placing the pieces of material in the shoes was adopted.

To eliminate the disadvantages in connection with the use of the pieces of material formerly employed, I have evolved the arrangement disclosed herein, which, briefly stated, comprises arranging a piece or pieces of rough faced material in the heel portion of a shoe, but instead of arranging my piece or pieces of rough faced material on the inner face of the shoe, as has been the case heretofore, I cut an opening or openings in the inner quarters of the shoe and set the piece or pieces of rough faced material in said opening or openings in such manner that the rough faces of the pieces of material are flush with the inside faces of the inner quarters of the shoe. By so arranging my piece or pieces of rough faced material the objectionable shoulders formerly present in the shoes at the pieces of rough material are eliminated and consequently the heel portion of the shoe is much more comfortable than heretofore and the likelihood that the wearer's stockings will be worn or sores or blisters formed on said wearer's heels is greatly reduced.

Fig. I is a view of a shoe provided with my improved means for preventing accidental relative movement between the heel portion of said shoe and the heel of the wearer thereof.

Fig. II is a cross section of the shoe shown in Fig. I looking rearwardly.

Fig. III is a section on line III-III of Fig. II.

Fig. IV is a view of a pair of inner quarters of a shoe showing said inner quarters as they will appear before the pieces of material have been cut therefrom.

Fig. V illustrates the step of cutting pieces of material from the inner quarters.

Fig. VI illustrates the inner quarters shown in Fig. IV after the pieces of material have been cut therefrom and after said pieces of material have been reversed and are being replaced in the openings from which they were cut.

Fig. VII is a fragmentary perspective of a pair of inner quarters showing the pieces of material secured in place and with a portion of one of said inner quarters broken away to show one of the backing members which are employed to secure said pieces of material in place.

In the drawings, A designates a woman's shoe of the low type which is made in the usual manner, said shoe including outer quarters B, inner quarters C and a counter 5 D. The shoe illustrated in the drawings includes also inner and outer soles, heel vamp, etc., but as these parts of a shoe are well known they will not be described herein. The material from which the inner quarters 10 C are cut is provided with a smooth face and a relatively rough face, as shown in Fig. VI, wherein the smooth face is designated by the reference character C^a and the rough face by the reference character C^b. In the 15 formation of a shoe the smooth sides C^a of the inner quarters are always exposed at the inside of the shoe as shown in Fig. I. The oppositely arranged inner quarters of a shoe are stitched or otherwise secured together 20 at the heel portion of the shoe, as shown in Figs. I, II and III, the line E indicating the meeting edges of said oppositely arranged inner quarters at which points the 25 stitches are located.

Formed in the oppositely arranged inner quarters C of the shoe A adjacent to the meeting edges E thereof are openings 1, said openings each having an open end at the edge E of the inner quarter in which it 30 is formed and being extended some distance inwardly from said edge E. By referring to Figs. I and II it will be seen that the openings 1 in the oppositely arranged inner quarters C are arranged in registration 35 with each other with the open end of one of said openings alined with and adjacent to the open end of the other opening, so that what is in effect a single opening is produced. Arranged in the openings 40 1 are sections of material 2, said sections of material being of the same contour as the openings 1 and said sections of material being set in said openings 1 so that the inner faces of said sections of material are flush 45 with the inner faces of the inner quarters C of the shoe. The inner faces of the sections of material 2, that is, the faces of said sections which are flush with the inner faces of the inner quarters C, are considerably 50 rougher than the inner faces of said inner quarters C, and said pieces of material are stitched together at their meeting edges indicated by the line F in Figs. I and II, said line F being in alinement with the line E 55 on which the inner quarters C are stitched together.

Located adjacent to the outer faces of the inner quarters C and the outer faces of the sections of material 2 are backing members 60 3, said backing members being formed of any suitable material, such, for instance, as leather. The backing members 3 are of the same general shape as the sections of material 2, there being one of said backing members for each individual section of the

material 2 and said backing members being of larger dimensions than said sections of material so that they overlap the edges of the openings 1 as shown in Fig. VII. The backing members 3 are each provided with a 70 face which is covered with an adhesive, as indicated by the reference character 4 in Fig. VII, said adhesive-bearing faces of said members being arranged adjacent to the outer faces of the inner quarters C and the outer faces of the sections of material 2. The adhesive 4 causes the backing members 3 to adhere to the inner quarters C and to the sections of material 2 whereby said sections of material are securely fixed in place 75 within the openings 1 in the inner quarters C. The associated backing members 3 of a shoe are provided with adjacent edges 3' which are alined with the meeting edges of the sections of material 2, and said associated backing members are stitched together at said adjacent edges preferably by the same stitches which secure the sections of material 2 together. 80

To insure the proper retention of the sections of material 2 within the opening 1 I employ a row of stitches 5 which pass through said sections of material 2 and through the backing members 3 and a second row of stitches 6 which pass through said 90 backing member 3 and through said inner quarters C, whereby said elements are securely fixed together.

In the use of a shoe provided with my improved means for preventing movement of 100 the heel portion thereof with respect to the heel of the wearer, the rough faces of the sections of material 2 will grip the stockings of the wearer and thus to a large extent prevent the objectionable rubbing of the shoe against the heel of the wearer, and because said sections of material are flush with the inner faces of the shoe no shoulders are present in the shoe which would render their use uncomfortable, and perhaps cause 110 damage to the stockings or produce sores or blisters on the heels of the wearer.

As already stated, the material from which the inner quarters C of my improved shoe are cut is provided with a smooth face C^a and a comparatively rough face C^b, and I take advantage of this fact to provide my improved shoe with a rough faced piece of material for preventing accidental movement of the heel portion of the shoe relative to the heel of the wearer without the addition to the shoe of a separate piece or pieces of material. 115

In accordance with the method followed in producing my improved shoe the inner 125 quarters are cut, after which said inner quarters are arranged face to face as shown in Fig. V and are introduced into an apparatus having die members G and H, which are adapted to cut sections of material 2 130

from said inner quarters C and form the openings 1. The sections of material 2 are then reversed as suggested in Fig. VI, and said sections of material are replaced in the openings 1 from which they were cut with the rough faces of said sections of material 2 flush with the smooth faces of the inner quarters C. The sections of material are then secured in place by means of the backing members 3 already referred to, said backing members being secured by means of an adhesive and by means of stitches to said sections of material and to said inner quarters, as shown in Fig. VII and already explained.

It is therefore plain that in accordance with my improved method a shoe is produced with rough faced pieces of material to prevent movement of the heel portion of the shoe relative to the heel of the wearer, without the use of additional pieces of material other than the relatively inexpensive backing members 3 whereby the cost of producing the shoe is less than it was heretofore when a separate piece of material was secured to the inside face of the shoe, and in addition to this a more comfortable shoe is produced because of the arrangement of the inner face of the rough faced section of material flush with the inner face of the shoe.

I claim:

1. In a new article of manufacture an apparel shoe having an inner quarter provided with a relatively smooth inner face, and means whereby the heel portion of said shoe is prevented from accidentally moving relative to the heel of the wearer, said means comprising a section of material having a roughened face, said roughened face of said section of material being arranged flush with the relatively smooth inner face of said inner quarter.

2. In a new article of manufacture an apparel shoe having an inner quarter provided with a relatively smooth inner face, and means whereby the heel portion of said shoe is prevented from accidentally moving relative to the heel of the wearer, said means comprising a section of material having a roughened face, said section of material being set into an opening in said inner quarter and said roughened face thereof being flush with the relatively smooth face of said inner quarter.

3. In a new article of manufacture an apparel shoe having an inner quarter provided with a relatively smooth inner face, means whereby the heel portion of said shoe is pre-

vented from accidentally moving relative to the heel of the wearer, said means comprising a section of material having a roughened face, said section of material being arranged so that its roughened face is flush with the relatively smooth face of said inner quarter, and a backing member, said backing member being secured to said section of material and to said inner quarter whereby said section of material is retained in position.

4. In a new article of manufacture an apparel shoe having inner quarters provided with relatively smooth inner faces, means whereby the heel portion of said shoe is prevented from accidentally moving relative to the heel of the wearer, said means comprising sections of material provided with roughened faces which are set into openings in said inner quarters and the roughened faces thereof being flush with the relatively smooth faces of said inner quarters, and means whereby said sections of material are retained in position, said means comprising backing members secured by means of an adhesive and by means of stitches to said sections of material and to said inner quarters, said backing members being arranged adjacent to the outer faces of said inner quarters.

5. The herein described method of making shoes which comprises cutting the inner quarters thereof from material one face of which is rougher than the opposite face thereof, cutting pieces of material from said inner quarters, reversing said pieces of material and replacing them in the openings thus formed in said inner quarters with the rough faces of said pieces of material flush with the smooth faces of said inner quarters, and then securing said pieces of material in position.

6. The herein described method of making shoes which comprises cutting the inner quarters thereof from material one face of which is rougher than the opposite face thereof, cutting pieces of material from said inner quarters, reversing said pieces of material and replacing them in the openings thus formed in said inner quarters with the rough faces of said pieces of material flush with the smooth faces of said inner quarters, and then applying backing members provided with faces having an adhesive thereon to said pieces of material and to said inner quarters whereby said pieces of material are secured in position.

In testimony that I claim the foregoing I hereunto affix my signature.

WALTER R. EKINS.
